Inventor

Oscar E. Uebergang

UNITED STATES PATENT OFFICE

2,172,303

SUPPORTING BOW

Oscar E. Uebergang, Benton, Ark.

Application December 17, 1938, Serial No. 246,448

1 Claim. (Cl. 296—118)

This invention relates to improvements in supporting bows particularly adapted for use in supporting any type of arched structure such as a tent, canopy or trailer cover.

5 It is the primary object of the invention to provide a bow formed of sections joined together by means of a releasable coupling which will permit folding of the sections when not in use.

10 A further object of the invention resides in providing a device of the above-mentioned character which is simple and durable in construction, reliable and efficient in use and inexpensive to manufacture.

15 Other objects and advantages of the invention will be apparent during the course of the following description.

In the accompanying drawing, forming a part of this specification and in which like numerals are employed to designate like parts throughout 20 the same,

Fig. 1 is a fragmentary elevation of a supporting bow constructed in accordance with my invention,

Fig. 2 is a similar view of the same showing the 25 sections of the bow in folded relation,

Fig. 3 is a top plan view of the coupling between the sections of the bow,

Fig. 4 is a side elevation of the coupling, and

Fig. 5 is a perspective view of the coupling with 30 the parts in separate relation.

In the drawing, wherein for the purpose of illustration I have shown a preferred embodiment of my invention, the numeral 5 denotes the supporting arch or bow which is divided at its center 35 to form sections 6 and 7 joined together by a coupling 8. The coupling consists of metal straps 9 and 10 secured to the top of the adjoining ends of the sections 6 and 7 by screws or other suitable fasteners 11. A T-shaped tongue 12 extends longitudinally from the center of the end of the strap 9 adapted to engage in the central longitudinal slot 13 formed in the end of the strap 10. A block 14 is secured to the underside of the strap 10 at its end extending transversely 40 of the slot 13 and a notch 15 is formed in the top side of the block in register with the slot to receive the stem of the tongue 12 and limit the swinging movement of the sections 6 and 7 in one direction. A pair of stop blocks 16 are secured to the underside of the strap 10 on opposite sides of the slot 13 and in spaced relation to the block 14 forming a groove 17 which receives the

head of the tongue 12 when the sections are in extended position. The strap 10 on the opposite side of the blocks 16 is provided with arched portions forming a recess 18 to receive the head of the tongue when the sections are swung into a folded position, as shown in Fig. 2.

5 In operation, the sections 6 and 7 are joined together by engaging the tongue 12 carried by one of the sections in the slot 13 of the strap carried by the other section. With the sections extended to form the supporting bow or arch the head of the tongue rests in the groove 17 and the stem of the tongue rests in the notch 15 in the block 14 limiting the movement of the sections. To fold the supporting bow or arch, the sections are swung outwardly and upwardly until the head of the tongue is free of the stop blocks and the stem is raised out of the notch 15, whereupon the sections are turned until one section is disposed over the other and then the head of 20 the tongue is disposed in the recess 18 which holds the sections in folded relation, as shown in Fig. 2. Thus, it is seen the supporting arch or bow may be compactly folded so as to be easily ported from place to place and yet at all times 25 the sections are securely coupled together.

It is to be understood that the form of my invention herein shown and described is to be taken as a preferred example of the same and that certain changes in the shape, size, and arrangement of the parts may be made without departing from the spirit of the invention or the scope of the subjoined claim.

Having thus described my invention, I claim:

A coupling for sectional bows comprising flat metal straps secured to the adjoining ends of the sections of the bow, one of said straps projecting beyond the end of the section and having a central longitudinal slot, a T-shaped tongue projecting longitudinally from the other strap adapted to engage in the slot of the first mentioned strap, and a cross block extending across the end of said first mentioned strap transversely of the slot, said block having a notch in its top side in register with the slot adapted to receive the shank of said tongue when the sections are extended, said first mentioned strap having upwardly arched portions on opposite sides of the slot forming a recess to receive the head of said tongue when the sections are swung into folded 45 relation.

OSCAR E. UEBERGANG.
